CLAIM

The ornamental design for medical equipment accessories and mounts in combination, as shown and described.

DESCRIPTION

FIG. 1 is a front perspective view of medical equipment accessories and mounts in combination;

FIG. 2 is a back perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The broken lines depicting a display monitor represent an environment, and all other broken lines illustrate portions of the medical equipment accessories and mounts in combination that form no part of the claimed design. The broken lines form no part of the claimed design.

1 Claim, 8 Drawing Sheets
